UNITED STATES PATENT OFFICE.

JUDSON C. JONES, OF INDEPENDENCE, KANSAS.

OIL-WELL REAMER.

1,371,425.

Specification of Letters Patent. Patented Mar. 15, 1921.

Application filed January 31, 1920. Serial No. 355,501.

To all whom it may concern:

Be it known that I, JUDSON C. JONES, a citizen of the United States, residing at Independence, in the county of Montgomery and State of Kansas, have invented certain new and useful Improvements in Oil-Well Reamers; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to reamers for oil wells and the like and one of the objects thereof is to provide means whereby the cavity at the bottom of a well may be efficiently reamed for cleaning or for other 20 purposes.

It is primarily the object of my invention to provide means whereby the reamer may be introduced into the well with the reaming elements in a collapsed or non-functioning position, and to provide means whereby, after the reamer is in position, mechanism may be operated for moving the reaming elements into functioning position and, further, to provide means whereby the reaming 25 elements may be maintained in contact with the walls of the well cavity during the operation of the reamer, the construction being such, however, that the remaining elements may be retracted to non-functional position 30 at the completion of the reaming operation so that the reamer may be readily withdrawn from the well.

Means is also provided for vertically adjusting the reamer within the well as well 40 as for causing rotative movement to be applied thereto so that the reaming elements may become effective for the purpose intended.

In the drawings,

45 Figure I is a side elevational view of a reamer constructed in accordance with my invention.

Fig. II is a vertical, longitudinal, sectional view of a reamer with the reaming 50 elements in non-functional position, ready to be inserted into the well.

Fig. III is a similar view, showing the reaming elements expanded into functional position.

Fig. IV is a fragmentary side elevational 55 view of a reamer casing.

Fig. V is a sectional view through a yoke for suspending the reamer in the well.

Fig. VI is a sectional view on the line 60 VI—VI of Fig. I, and

Fig. VII is a slightly modified form of yoke.

1 designates a well, in the bottom of which is a cavity which may consist of the stages 2, 3 and 4, the construction of the 65 cavity, however, being immaterial. 5 is a well lining or casing and about the top thereof is a frame 6, supporting a shaft 7 carrying a pulley 8, by means of which the shaft 7 may be driven from any suitable 70 source of power, and said shaft 7 is shown as provided with a beveled pinion 9, meshing with a gear 10 adapted to rotate a shaft 11, slideable with respect to the gear 10, the rotation being effective through the medium 75 of an upstanding arm 12 on the gear, which may contact with a vertically adjustable lever arm 13 on shaft 11, which may be suspended from any suitable source through the medium of a yoke 14, carrying a collar 80 15, loose on shaft 11 and supporting the anti-friction bearings 16 for the collar 17 fastened on shaft 11. The shaft 11 is provided with a pressure pipe inlet 18, whereby pressure from the pipe 19 may be introduced 85 into the hollow rod or shaft 11 to actuate certain reaming mechanism, to be referred to hereinafter. The hollow rod or shaft 11 is connected to a reamer cylinder or tube 20 by a connection 21, as will be apparent 90 by reference to Figs. I, II and III.

The cylinder or tube 20 is provided with a pressure chamber 22, one end of which communicates with the hollow rod or shaft 11, the other end being closed by a plug 95 disk 24, against which one end of a coil spring 25 abuts, the opposite end of the coil spring being fastened at 26 to an actuating rod 27 projecting through a stuffing box 28 in the plug 24 and extending the entire 100 length of the subjacent chamber 29 of the cylinder 20. The lower end of the rod 27 carries a cap 30 which is adapted to abut against the lower end of the tube 20 to provide a stop to limit the upward movement 105 of the rod 27 under the action of the spring 25 and said stop or disk 30 is of greater diameter than the diameter of the tube 20

and carries at its periphery an upstanding flange 31, adapted to receive the free ends 32 of the radial reamer arms 33, pivoted in the openings 34 of the tube 20. The arms 33 have inwardly and downwardly projecting spreader-engaging portions 35, adapted to contact with the conical spreaders 36 carried by the rod 27 and adapted to move into spreading position under the influence 10 of pressure in chamber 22, exerted against the piston 37 on rod 27 and moving in opposite direction to the force exerted by the spring 25.

When the arms 33 are swung outwardly, 15 they are guided in proper spaced relation by the slots or notches 38 in the rigid collar 39 fastened to the tube 20, the upper edges of the notches serving as stops which also aid in affording rigidity to the arms at their 20 points of connection so that they will maintain as nearly as possible true radial positions with respect to the tube. When the expander 36 moves in an upward direction, the arms 33 will, by gravity, drop close to 25 the tube and since the retraction of the expander moves slightly in advance of the retaining collar 31, the ends 32 will drop into position to be embraced by the flange 31 and be held in retracted position, as clearly 30 seen in Fig. II.

The sets of arms may be multiplied to suit conditions and I have here illustrated three sets of arms, the lower set being just described and the two upper sets being substantially the same in construction as the one just described with the exception of the retaining means. In place of the cap 31, the upper sets are provided with sliding collars 40, secured to the rod 27 by the cross arms 41, the cross arms 41 operating in slots 42 in the tube 20. The rigid collars, the arms and the expanders for the secondary sets are substantially like those just described and it is, therefore, deemed unnecessary to again 45 describe these in detail, it being sufficient to indicate that the flange collars 41 move up into position to receive the ends 32 of the arms 33 in substantially the same way as the flange disk 30 heretofore described.

50 If desired, the chamber 22 may be provided with a lining 43, this generally being desirable because the cylinder 20 will be constructed of rough, unmachined tubing or piping, it being desirable to provide a 55 smooth surface for the packing of the piston 37.

When the parts are assembled as shown in Figs I to VI, the shaft 7 can be rotated from a suitable power source to rotate the 60 rod or shaft 11 through the medium of the gears 9 and 10, it being understood that the shaft or rod 11 is suspended from the yoke 14. If the valve 44 in the pipe 19 is opened to admit pressure into the chamber 22, the 65 piston 37 will be actuated against the spring

25 to move the conical reamer element spreaders into functioning position so that they will contact with the ends 35 of the arms 33 and exert a tendency to expand the group radially. Since the retainers, 70 consisting of the flanged disk 30 and the collars 40, move with the rod 27 and therefore, with the expanders, the movement of the expanders into functioning position will result in moving the retainers into non-functioning position; that is, when the expanders move into functioning position, the reamer arm retainers move out of holding position, and vice versa. As the piston moves under the pressure of the fluid in the 80 chamber 22, the arms will be forced to as nearly horizontal positions as the side walls of the cavity of the well will permit and by maintaining a pressure upon the piston 27 during the rotative movement of the rod 11 and the cylinder 20, contact of the arms 85 with the wall of the cavity will be maintained at all times.

The reamer may be raised and lowered 90 during the reaming operation through the medium of the yoke, the length of the arm 12 permitting a limited movement of the reamer because the reamer will be rotated with the arm 13 in any position between the ends of the arm 12. If it is desired to lower 95 the reamer to a position in excess of the length of the arm 12, the arm 13 will be loosened and adjusted for this purpose.

I prefer to arrange the sets of reamer arms in progressively decreasing lengths or sizes 100 since the top of the chamber may be initially reamed to one size by the top reamer, that stage of the cavity being enlarged by the second reamer and finally completed by the third, if three reaming sets are employed. 105 The exact arrangement of the reamer arms, however, is not deemed an essential part of the invention.

In Fig. VII I have shown a slightly modified form of rod connection for the expanders. In this form, the cylinder or tube 20 is capped at its upper end by a cap 45, which supports a threaded rod 46, the threaded end 47 carrying a nut 48 adapted to be engaged by a wrench or other suitable tool to 115 be adjusted upon the threads 47 whereby the rod 46 may be raised and lowered so as to move the expanders 36 into and out of functional position. If this construction is used, the piston, the air pressure and the 120 retracting spring may be dispensed with, but where air is available, I prefer to utilize the air actuated device on account of convenience of operation.

From the foregoing it will be apparent 125 that the device may be easily introduced into the well, and that upon opening the valve 44 or its equivalent, the reamer arm sets may be expanded into functioning position and upon the completion of the work, they will 130

be retracted into non-functioning positions whereby the tool may be withdrawn from the well in an easy and expeditious manner.

What I claim and desire to secure by Letters-Patent is:

1. An oil well reamer device comprising a cylinder, arms having hook-shaped ends engaging apertures in the cylinder wall, a rod having movement longitudinally of the cylinder, an expander on the rod to press against the hook-shaped ends when the rod is moved in one direction, an arm retainer on the rod to engage the outer ends of the arms when the rod is moved in an opposite direction, and means for operating the rod. 10
2. An oil well reamer comprising a cylindrical member having openings in the wall thereof, arms having hook-shaped ends loosely engaging the openings whereby the arms are pivotally connected to the wall of the cylindrical member, and an expanding device movable longitudinally in the cylindrical member. 20
3. An oil well reamer comprising a cylindrical member having openings in the wall thereof, independently mounted arms having hook-shaped ends extending through the openings with the terminals of the hook-shaped ends projecting within the cylindrical member, and an expanding member movable longitudinally within the cylindrical member. 30
4. An oil well reamer comprising a cylindrical member having openings in the wall thereof, independently mounted arms having

hook-shaped ends extending through the openings with the terminals of the hook-shaped ends projecting within the cylindrical member, an expanding member movable longitudinally within the cylindrical member, 40 a rod for operating said expanding member, and arm-end engaging devices fixed to the rod.

5. An oil well reamer comprising a cylindrical member having openings in the wall thereof, independently mounted arms having hook-shaped ends extending through the openings with the terminals of the hook-shaped ends projecting within the cylindrical member, an expanding member movable 45 longitudinally within the cylindrical member, a rod for operating said expanding member, and arm-end engaging devices comprising upwardly flanged disks fixed to the rod. 50

6. In an oil well reamer, a cylindrical member having openings in the wall thereof, a fixed collar adjacent to the openings, the lower edge of which is slotted, independently mounted arms having hook-shaped 60 ends extending through the slotted portion of the collar and through the openings in the cylindrical member, the inner ends of the hooks projecting within the cylindrical member, a conical expanding member for 65 contact with the hooked ends of the arms, and means for actuating said expander.

In testimony whereof I affix my signature.

JUDSON C. JONES.
